US0D1000644S

(12) **United States Design Patent** (10) **Patent No.:** **US D1,000,644 S**
(45) **Date of Patent:** **** Oct. 3, 2023**

(54) **SPIKED EDGING**

(71) Applicant: **Hebei Minmetals Co., Ltd.**,
Shijiazhuang (CN)

(72) Inventor: **Kebiao Hu**, Shijiazhuang (CN)

(73) Assignee: **HEBEI MINMETALS CO., LTD.**

(**) Term: **15 Years**

(21) Appl. No.: **29/775,858**

(22) Filed: **Mar. 25, 2021**

(51) LOC (14) Cl. **25-01**

(52) U.S. Cl.

USPC **D25/164**

(58) **Field of Classification Search**

USPC D25/136–137, 164, 199

CPC A01G 9/00; A01G 9/28; Y10S 30/05

See application file for complete search history.

(57) **CLAIM**

The ornamental design for a spiked edging, as shown and described.

DESCRIPTION

FIG. 1 is a front side perspective view;

FIG. 2 is a back side perspective view;

FIG. 3 is a front side elevation view;

FIG. 4 is a back side elevation view;

FIG. 5 is an enlarged, right side elevation view;

FIG. 6 is an enlarged, left side elevation view;

FIG. 7 is a top plan view;

FIG. 8 is a bottom plan view;

FIG. 9 is an enlarged perspective view, taken at 9 in FIG. 1;

FIG. 10 is an enlarged perspective view, taken at 10 in FIG. 2;

FIG. 11 is an enlarged perspective view, taken at 11 in FIG. 1;

FIG. 12 is an enlarged perspective view, taken at 12 in FIG. 2;

FIG. 13 is an enlarged perspective view, taken at 13 in FIG. 1; and,

FIG. 14 is an enlarged perspective view, taken at 14 in FIG. 2.

The broken lines depict the boundaries of the enlargements and form no part of the claimed design.

1 Claim, 11 Drawing Sheets
